UNITED STATES PATENT OFFICE.

WILLIAM H. COLDWELL AND HARRY T. COLDWELL, OF NEWBURG,
NEW YORK.

BEARING ADJUSTMENT.

SPECIFICATION forming part of Letters Patent No. 669,436, dated March 5, 1901.

Application filed October 25, 1900. Serial No. 34,288. (No model.)

To all whom it may concern:

Be it known that we, WILLIAM H. COLDWELL and HARRY T. COLDWELL, citizens of the United States, residing at Newburg, in the county of Orange and State of New York, have invented certain new and useful Improvements in Bearing Adjustments for Lawn-Mowers; and we do hereby declare the following to be a full, clear, and exact description of the invention, such as will enable others skilled in the art to which it appertains to make and use the same.

Our invention is an improvement in adjusting mechanism for lawn-mower bearings; and it consists in the novel features hereinafter described, with reference to the accompanying drawings, which illustrate one form in which we have contemplated embodying our invention, and said invention is fully disclosed in the following description and claims.

Referring to the said drawings, Figure 1 represents a top plan view of a lawn-mower embodying our invention. Fig. 2 is a detail sectional view of part of the same, showing our improved adjusting mechanism; and Fig. 2^a is a section on line 2^a 2^a of Fig. 2. Fig. 3 is a view showing the parts of the adjusting mechanism detached. Fig. 4 is a view similar to Fig. 2, showing a slight modification of our invention.

The object of our invention is to provide a cheap, strong, and efficient means for adjusting the ball-bearings of the rotary cutter of a lawn-mower.

In the drawings, A represents the mower-frame, which is of usual construction and is provided with two side frames a.

B represents the stationary knife; C, the bail; D, the handle; E, the roller, and F F the driving-wheels which operate the rotary cutter. The rotary cutter in this instance consists of two spiders G G, the arms of which are riveted to the spiral blades g. Each spider is provided with a shaft or trunnion g', which extends through an aperture a' in the adjacent side frame a and is provided with a pinion g², driven from one of the driving-wheels F F in the usual manner. Each side plate a is provided with a bearing-cup H, concentric with the aperture a' in the frame a, and we prefer to provide each side

frame with a circular flange a², concentric with said aperture a', forming a socket to receive the said cup H, as shown. One of the trunnions g' is provided with a fixed cone g³, 55 engaging one of the cups H, and the other trunnion H is provided with an adjustable cone g⁴. (Shown in detail in Figs. 2 and 3.) This cone g⁴ is provided with a central aperture g⁵, which fits the trunnion g', and also 60 with a threaded aperture g⁶, having its axis parallel to the axis of said trunnion. The cone g⁴ is also provided with a radial threaded aperture g⁷ to receive a set-screw I, which is adapted to pass through the cone and engage 65 the trunnion g'.

The spider G adjacent to the adjustable cone is provided with a threaded aperture g⁸, so arranged that its axis will coincide with the axis of the aperture g⁶ when the cone is 7c turned so as to bring the two apertures into line, but of greater diameter than the said aperture g⁶.

K represents a double-acting adjusting-screw having two oppositely-threaded parts 75 k and k' of different diameters, the part k being adapted to screw into the aperture g⁶ of the cone, and the larger part, k', being adapted to screw into the aperture g⁸, as shown. The screw K is provided with a nick 80 in its head, as shown, (or with a polygonal head,) so that it can be turned.

L represents the balls, which are interposed between the cups H and the cones g⁴.

To adjust the bearings of the rotary knife, 85 the set-screw I is loosened, and the adjusting-screw K is turned to move the adjustable cone toward or away from its cup H, thereby adjusting both of the bearings simultaneously. The screw K will move the cone in either direction, and a very slight rotation of the screw will move the cone a considerable distance. As the screw K engages the cone at one side of its center, it may have a tendency to twist the cone slightly upon the shaft. The set-screw I is therefore located substantially at right angles to a plane passing through the axes of the screw K and trunnion g', as shown, so that when it is tightened up after the cone has been adjusted it will draw the cone and 90 trunnion tightly together on the opposite side, and as the central aperture in the cone is true 100

and also the exterior of the trunnion this will correct any tendency of the adjusting-screw K to throw the cone g^4 out of line.

We prefer to form the shaft or trunnion g' 5 with an inclined or beveled portion i beneath the set-screw I, as shown in Fig. 2^a, so arranged that the engagement of the screw with the said beveled portion i will tend to throw the cone outward on the shaft, and thus cause 10 it to act like a jam-nut on the adjusting-screw K. This prevents the possibility of the screw K turning accidentally while the mower is in use.

In some cases we may dispense with the aperture g^6 in the cone and employ an ordinary adjusting-screw with a single thread passing through the spider, as shown in Fig. 4. In this figure, G' represents the spider; G², the 15 rotary-cutter shaft; M, the cone; N, the adjusting-screw; O, the set-screw, and P the cup.

In Figs. 1 and 2 we have shown the spiders of the rotary cutter formed integrally with the trunnions $g' g'$; but it is obvious that they may be mounted upon and secured to a shaft 25 extending across the machine and having its ends projecting beyond the spiders to form the trunnions. Such a construction is indicated in Fig. 4, where the shaft G² passes through the spiders, which are secured to the 30 shaft by set-screws, as indicated at G³.

What we claim, and desire to secure by Letters Patent, is—

1. An adjusting device for bearings comprising among its members, a bearing-cup, a 35 rotary part provided with an adjustable cone, an adjusting-screw passing through said rotary part and engaging said cone at one side of its center, and a set-screw extending radi-

ally through said cone at an angle to a plane passing through the centers of said cone and 40 adjusting-screw and engaging said rotary part, substantially as described.

2. An adjusting device for bearings comprising among its members, a rotary part, a bearing-cone adjustable longitudinally thereon, a single adjusting-screw having a threaded portion engaging a threaded aperture in a part connected with said rotary part, and a reversely-threaded portion engaging a threaded aperture in said cone at one side of its 50 center, and a set-screw extending through a radial threaded aperture in said cone, substantially perpendicular to a plane passing through the centers of said cone and said adjusting-screw, substantially as described. 55

3. An adjusting device for bearings comprising among its members, a bearing-cup, a rotary shaft, a cone loosely mounted thereon and provided with a threaded aperture having its axis parallel with the axis of the cone, 60 a rotating part secured to said shaft provided with a threaded aperture, a single adjusting-screw having reversely-threaded portions engaging said apertures in the rotating part and in said cone and a set-screw extending radially through said cone at an angle to a plane 65 passing through the centers of the cone and the adjusting-screw therein parallel to said axis, substantially as described.

In testimony whereof we affix our signatures in the presence of two witnesses.

WILLIAM H. COLDWELL.

HARRY T. COLDWELL.
